UNITED STATES PATENT OFFICE.

GEORGE A. EYNON, OF CLEVELAND, OHIO, ASSIGNOR TO THE UNIVERSAL CARBURETOR COMPANY, OF CLEVELAND, OHIO, A CORPORATION OF OHIO.

APPARATUS FOR GASIFYING LIQUIDS.

1,181,515.

Specification of Letters Patent.

Patented May 2, 1916.

Application filed August 8, 1914. Serial No. 855,894.

To all whom it may concern:

Be it known that I, GEORGE A. EYNON, a citizen of the United States, and a resident of Cleveland, county of Cuyahoga, and State of Ohio, have invented a new and useful Improvement in Apparatus for Gasifying Liquids, of which the following is a specification, the principle of the invention being herein explained and the best mode in which I have contemplated applying that principle, so as to distinguish it from other inventions.

My invention relates to apparatus for vaporizing and gasifying liquids.

More particularly, my invention relates to apparatus suitable for use in vaporizing and gasifying fuels for use in operating internal combustion engines.

As a particular illustration of my improved apparatus, I shall describe herein-after means which successfully vaporize and gasify petroleum, not only the lighter distillates but also the heavier distillates, especially all grades of kerosene or even crude oil, particularly a carburetor construction suitable for carrying out the vaporizing and gasifying of petroleum for use in automobiles and allied mechanisms.

By thus referring to the use of the present invention in connection with internal combustion engines, I do not mean to limit the same to this use, as many other adaptations of the invention will readily suggest themselves to men skilled in the various arts.

To the accomplishment of the foregoing and related ends, said invention, then, consists of the means herein-after fully described and particularly pointed out in the claims.

The annexed drawings and the following description set forth in detail certain means exemplifying the invention, such disclosed means illustrating, however, but one of various ways in which the principle of the invention may be used:

In said annexed drawings, Figure 1 is a central vertical section of the means herein described, illustrating the principle of my invention; Fig. 2 is an elevation of the same; Fig. 3 is a horizontal section upon the lines 3—3, Fig. 1; Fig. 4 is a vertical section and elevation upon the lines 4—4, Fig. 3; Fig. 5 is a broken vertical section upon the lines 5—5, Fig. 3, illustrating particu-

larly the mixing and combustion chambers and the ignition devices, hereinafter fully described; Fig. 6 is a broken perspective view of the choke-plates hereinafter fully described; and Fig. 7 is a vertical section upon the line 7—7, Fig. 1.

Referring to the annexed drawings, 1 represents a fuel supply pipe, 2 a screen or filter, 3 a float needle valve opening regulated by float needle valve 4 operated by float 5 and levers 6 by which a constant level of fuel is maintained in the fuel chamber.

Fuel passes through the passage 7 toward the preliminary mixing chamber 8, the flow being regulated by the adjusting shaft 9 acting as a valve at 10, said shaft being provided with a threaded portion which causes it upon being turned to regulate the flow of fuel at 10. This regulation is effected as follows: A lever 38 is secured to shaft 9 and a ratchet-wheel 39 is rotatably mounted upon the said shaft and is engaged by an opening connection 40 which is secured to the lever 38. An adjusting lever 37 is rotatably mounted upon the shaft 9, is secured to ratchet wheel 39, and is hinged to a connecting link 36 which in turn is hinged to an adjusting lever 32 provided with extended lugs 33. Lever 32 is actuated by the movement of the shaft 29 upon which is mounted a butterfly valve 28 of standard design for controlling the amount of gas given to the engine. Shaft 29 is operated by means of lever 30 and connecting rod 31. The limits of movement for opening and closing the valve 28 are fixed by the adjusting screw 34 and stop lug 35 against which the extended lugs 33 on the adjusting lever 32 strike. Assuming then that the fuel controlled as desired is being fed into the preliminary mixing chamber 8, the apparatus

is designed to vaporize the fuel within the spirit of the invention described and claimed in my pending application for United States Letters Patent Serial No. 794,266 (series of 1900) in that a plurality of separated columns of vaporized fuel are formed and mixed with air and then these separate columns are intermixed. This preliminary mixing and then the intermixing are accomplished as described in said pending application by means of an upper and a lower baffling plate 8¹ and 8² respectively provided with spaced apertures 12 and 13 through which the air from the primary air open-

ing 11 passes. The openings 12 are larger than the openings 13 but said openings 12 and 13 correspond in number and position. The fuel passes from the passage 7 laterally into the preliminary mixing chamber 8 and is caught up and vaporized by the air currents through the openings 13 and 12, thus forming a number of separate columns of mixed vapor and air. The lateral movement of the fuel and the size and position of the apertures 12 set up eddy currents in the separate columns thus preliminarily mixing the fuel and air. The preliminary mixing chamber 8 is smaller in diameter than the mixing and combustion chamber proper 17, the upper part of which will be hereinafter fully described as a combustion chamber, so that some air passes up around said preliminary mixing chamber 8. Upon emerging from the apertures 12, the separate columns of vaporized fuel intermix, the resulting product being an extremely intimate intermixture of the vaporized liquid and air, the proportions of each being controlled by the relative sizes of the air and fuel supply conduits, as well as by the proportions of the apertures 12 and 13 in the plates 8¹ and 8² of the preliminary mixing chamber.

For the purposes of starting up the automobile engine, the vaporized fuel is gasified by means of a heating element 14 through which an electric current is passed which gasifies the fuel absorbed by a wicking 15 about which the coil 14 is wound. Said wicking is comprised of non-combustible and as far as possible non-destructible absorbent material and is placed above the preliminary mixing chamber 8, being held in place by the heating element 14 and further held in place by a metal collar 14¹ which is fastened to or can be made integrally with the upper plate 8¹ of the preliminary mixing chamber 8, said collar 14¹ being inside of the apertures 12 so that said wicking 15 lies in an idle or semi-idle spot. A part only of the fuel being drawn through is thus heated by the heating element 14. A spark plug 16 is inserted over the wicking 15 and a spark is produced at the idle or semi-idle spot which starts into a flame the highly vaporized liquid produced by the action of the heating element 14. The entire combustion chamber 17 is thus immediately filled with fire or flame and the vaporized liquid continuously drawn forward by the suction of the engine passes through this flame. The spark plug has one electrode at 25 which grounds the high tension current. In order that the aforementioned flame may not pass into the engine and in order that no more than a small per cent. of the vaporized liquid may be burned or consumed by the flame, choke plates 18 and 19 are provided, the former having annular rows of holes 20 and downwardly pro-

jecting tubes 21, and the latter a central hole 53 leading into the auxiliary air opening 54. The purpose of the tubes 21 is to spread the flame in the combustion chamber 17 and thus keep the latter full of flame. These plates 18 and 19 effectually check the flame and allow the highly gasified products of the incomplete combustion to pass through to be mixed with the auxiliary air and then through the intake manifold to the engine cylinders. In order to make the action more positive and to sustain the supply of gas at all times, a supplementary non-combustible, non-destructible wicking 22 is provided which is placed on top of the upper plate 8¹ of the preliminary mixing chamber 8 outside of the apertures 12 and adjacent to the outer wall of said preliminary mixing chamber, being held in place by means of annular rings 22¹ formed integral 85 with said chamber 8. In order to better control and check the flame in the combustion chamber 17, a baffle plate 23 is provided below the choke plate 18 of somewhat smaller diameter than the diameter of the combustion chamber which forces the flame outwardly thus assisting in the control of the same. Said baffle plate 23 is provided with an aperture 23¹, Fig. 5, located over the spark gap and which serves to promote a slight current or air movement past the spark point thus sustaining the fire or flame. An additional non-combustible, non-destructible wicking 24 is carried on top of the baffle plate 23 which further helps to sustain the flame and to make the action positive under all running conditions. In the event that the heating element 14 has failed for the purposes of starting the engine, I use the priming tube 26 connected 100 with the priming cup 27 into which latter may be poured a light fuel. After the engine has been effectually started, the use of the heating element 14 is discontinued. The auxiliary air intake 54 is supplied 110 through the valve 41 guided by pin 41¹ and controlled by spring 42. The latter is adjustably seated on 43 and locked thereon in any predetermined position by means of lock screw 44 and the latter is adjusted by cap 46 which is in turn held in any predetermined position by spring 45. A dust cup 47 is also provided. As the suction from the engine increases, the valve 41 opens and is held by spring 42. A supplementary air valve 48 is provided having openings 49 which is rotatably mounted on a pin 50 and is held by a spring 51. The air passes through the openings 49 thence through the openings 52 in the carburetor body and mingles with the gas drawn through opening 53 from the combustion chamber 17. The valve 48 is set and the openings 49 are constant.

The foregoing apparatus has been found 130

to secure a complete gasification not only of the light distillates of petroleum, but also of the heavy distillates such as all grades of alcohol, kerosene and crude oil. The satisfactory use of these heavier distillates effects a great economy in the cost of operation of internal combustion engines. The true gas that I thus obtain from the heavier distillates is obtained at ordinary atmospheric pressure and is a gas of a different quality than is produced by any apparatus with which I have heretofore been acquainted in that for a long period it will not condense at ordinary atmospheric temperatures, a gas which when further mixed with air is very highly explosive and which leaves little or no carbon or other deposit in the cylinders, and creates very little smoke at the exhaust. By the use of the heating element described, in combination with the preliminary mixing chamber which of itself intimately mixes and highly vaporizes the fuel and air, it is not necessary to use the light distillates for starting the engine in order to raise the temperature of the working parts. The apparatus described has a very broad field of operations, in that gasoline and other light distillates may be gasified without the aid of the heating device or the ignition device; also without the aid of these devices, my invention will more highly vaporize kerosene and the heavy distillates than any other apparatus with which I am acquainted; and with the aid of these devices will convert these heavy distillates into a true gas highly satisfactory even for the starting of the engine. I desire to particularly point out that the combination of elements which I have described procures very positive action of the engine under all running conditions. Furthermore, I desire to point out that, inasmuch as it is not necessary to rely on the heat of the exhaust gases, my invention can be applied to any type of internal combustion engine regardless of the position of the exhaust manifold.

The various uses to which my improved apparatus can be applied will readily suggest themselves to those skilled in the various arts. The invention has already been successively applied to the gasification of kerosene for use in internal combustion engines, and it is for this reason that the foregoing description has dealt with such an application of the invention as affording the best and clearest illustration of the preferred forms of the apparatus.

The method of gasifying liquids of which the use of the apparatus herein described, and hereinafter claimed, is an illustration, will form the subject matter of another application for United States Letters Patent.

I claim—

1. In apparatus of the character described, the combination of fuel and air sup-

ply means; a mixing chamber; absorbent material in said chamber; a heating element disposed in juxtaposition to said absorbent material; an ignition device intersecting the path of travel of the mixture; and baffling devices adapted to extinguish the flame caused by said ignition device.

2. In apparatus of the character described, the combination of fuel and air supply means; a mixing chamber; an absorbent wicking in said chamber; a heating element adapted to gasify the fuel absorbed by said wicking; a spark plug intersecting the path of travel of the mixture; and baffling devices adapted to extinguish the flame caused by said spark plug.

3. In apparatus of the character described, the combination of fuel and air supply means; a mixing chamber; an absorbent material disposed in a substantially idle spot in said chamber; a heating element adapted to gasify the fuel absorbed by said material; an ignition device intersecting the path of travel of said gasified fuel; and baffling devices adapted to extinguish the flame caused by said ignition device.

4. In apparatus of the character described, the combination of fuel and air supply means; a mixing chamber; an absorbent wicking disposed in a substantially idle spot in said chamber; a heating element adapted to gasify the fuel absorbed by said wicking; a spark plug intersecting the path of travel of said gasified fuel; means adapted to spread the flame caused by said spark plug; and baffling devices adapted to extinguish said flame.

5. In apparatus of the character described, the combination of fuel and air supply means; a preliminary mixing chamber and a main mixing chamber, part of said air being intimately intermixed with said fuel in said preliminary mixing chamber whereby said fuel is vaporized and the balance of said air being intermixed with said vaporized fuel in said main mixing chamber; an absorbent material in said latter chamber; a heating element adapted to gasify the vaporized fuel absorbed by said material; an ignition device intersecting the path of travel of the mixture; and means adapted to extinguish the flame caused by said ignition device.

6. In apparatus of the character described, the combination of fuel and air supply means; a preliminary mixing chamber and a main mixing chamber, part of said air being intimately intermixed with said fuel in said preliminary mixing chamber whereby said fuel is vaporized and the balance of said air being intermixed with said vaporized fuel in said main mixing chamber; an absorbent wicking disposed intermediately of the active spots in said latter chamber; a heating element adapted to gasify the va-

porized fuel absorbed by said wicking; a spark plug intersecting the path of travel of said gasified fuel; and means adapted to extinguish the flame caused by said spark

5 plug.

7. In apparatus of the character described, the combination of fuel and primary air supply means; a preliminary mixing chamber and a main mixing chamber, part of 10 said primary air being intimately intermixed with said fuel in said preliminary mixing chamber and the balance of said primary air being intermixed with said fuel in said main mixing chamber; a spark plug 15 intersecting the path of travel of the mixture; baffling devices adapted to extinguish the flame caused by said spark plug; and means adapted to furnish auxiliary air to mix with the highly gasified fuel produced 20 by said flame.

8. In apparatus of the character described, the combination of fuel and air supply means; a mixing chamber; an absorbent material in said chamber; a heating element 25 adapted to gasify the fuel absorbed by said material; an ignition device intersecting the

path of travel of the mixture; means adapted to produce an air movement past the ignition device; and baffling devices adapted to extinguish the flame caused by said ignition device. 30

9. In apparatus of the character described, a flame-baffling device comprising two opposed plates, one provided with a plurality of apertures, and the other with a comparatively large aperture laterally located respective to said aforementioned apertures. 35

10. In apparatus of the character described, a flame-baffling device comprising two opposed plates, one provided with a 40 plurality of projecting tubes and a plurality of apertures, and the other with a comparatively large central aperture laterally located respective to said aforementioned tubes and apertures. 45

Signed by me, this 3rd day of August 1914.
